[57] CLAIM

The ornamental design for a dispenser for air treating material, as shown.

DESCRIPTION

FIG. 1 is a front elevational view of a dispensing air treating material, in a fully closed position, showing my new design;

FIG. 2 is a side elevational view thereof;

FIG. 3 is an exploded front elevational view thereof;

FIG. 4 is a top plan view thereof; and

FIG. 5 is a bottom plan view thereof.
